UNITED STATES PATENT OFFICE

105,664

DESIGN FOR A CHAIR

Leo Jiranek, New York, N. Y., assignor to Heywood-Wakefield Company, Gardner, Mass., a corporation of Massachusetts

Application July 6, 1937, Serial No. 70,266

Term of patent 3½ years

To all whom it may concern:

Be it known that I, Leo Jiranek, a citizen of the United States and a resident of New York, county of New York, and State of New York, have invented a new, original, and ornamental Design for a Chair, of which the following is a specification, reference being had to the accompanying drawing, forming a part thereof, in which the figure is a perspective view of a chair showing my new design, the characteristic feature of the design being embodied in the sides of the chair as shown.

I claim:

The ornamental design for a chair substantially as shown and described.

LEO JIRANEK.
